UNITED STATES PATENT OFFICE

148,177

DESIGN FOR A BODY FOR A HOBBYHORSE

Carl D. Madsen, Brigham, Utah

Application July 8, 1946, Serial No. 131,353

Term of patent 14 years

(Cl. D34—15)

To all whom it may concern:

Be it known that I, Carl D. Madsen, a citizen of the United States, residing at Brigham, in the county of Box Elder and State of Utah, have invented a new, original, and ornamental Design for a Body for Hobbyhorses, of which the following is a specification, reference being had to the accompanying drawings, forming part thereof.

Figure 1 is a side elevation of the body for a hobbyhorse, showing my design both sides of which are identical; and Figure 2 is a plan view thereof.

I claim:

The ornamental design for a body for a hobbyhorse, as shown and described.

CARL D. MADSEN.
